Patented Feb. 1, 1966

203,637

ROTARY DISPLAY RACK

Sidney Bernstein, Clark, N.J.
(1608 W. Edgar Road, Building O, Linden, N.J.)

Filed Apr. 21, 1964, Ser. No. 79,632

Term of patent 14 years

(Cl. D80—9)

FIG. 2.

FIG. 1.

FIGURE 1 is an elevational view of a rotary display rack embodying my new design; and

FIGURE 2 is a top plan view thereof.

I claim:

The ornamental design for a rotary display rack, as shown and described.
